UNITED STATES PATENT OFFICE.

JOHN T. WHALEN, OF BROOKLYN, NEW YORK, ASSIGNOR, BY DIRECT AND MESNE ASSIGNMENTS, TO THE WHALEN COMPANY, OF JERSEY CITY, NEW JERSEY, A CORPORATION OF NEW JERSEY.

PERMUTATION-LOCK.

No. 923,743.

Specification of Letters Patent.

Patented June 1, 1909.

Application filed June 27, 1907. Serial No. 381,059.

To all whom it may concern:

Be it known that I, JOHN T. WHALEN, a citizen of the United States of America, and a resident of Brooklyn, county of Kings, and 5 State of New York, have invented certain new and useful Improvements in Permutation-Locks, of which the following is a specification.

This invention relates to improvements in 10 permutation locks, and its object is to render such locks safer and more convenient in their use, and to simplify their manufacture.

Furthermore, the aim of my invention is to 15 arrange the parts, relatively one to the other, so that the combination may be changed from without only by the person knowing the same, or when the lock is open, and that when such a changing of the combination is effected, or at any other time, the knobs on 20 the outside of the box cannot be removed or become lost, except through opening the lock and taking same apart from within.

In the accompanying drawing forming 25 part of this specification, in which like characters of reference indicate like parts in all the views, Figure 1 is a front or outside view of such a lock. Fig. 2 is a rear view of the same. Fig. 3 is a vertical, central section on line A—A of Fig. 1. Fig. 4 is a transverse 30 section on line B—B of Fig. 3, and Fig. 5 is a transverse section on line C—C of Fig. 3.

Referring to the drawing, my permutation lock is shown to consist, in the main, of a lock-plate *a*, three disks or tumblers, as *b c d*, having tubular extensions which latter project through an opening in the said lock-plate, see Fig. 3, and three knobs or rings, as *g f e*, which engage with the ends of the central tubular extensions of the said disks *b c d*, 40 respectively, a central member or screw *h* serving to hold together the disks and their knobs and to secure same rotatably to the lock-plate *a*. Each one of the disks *b c d* is provided, on its periphery, with a number of 45 shallow slots or kerfs, as *n*, and one kerf, as *m*, which is considerably deeper, all of which kerfs are equidistant. The shallow kerfs *n* serve to engage with a spring, as *s*, to aid in obtaining a step by step motion of each disk, 50 while maintaining the other disks in their positions of rest, in accordance or corresponding with the marks or numbers on the knobs, for the purpose of placing the three disks, successively, in such a position, relative to 55 one another, so that their deep kerfs *m* are in line to receive the corresponding end of lever *r* and thereby cause an unlocking of the box to which the lock may be attached.

Each one of the three disks *b c d* has a slot, as *b' c' d'*, which slots connect with the central 60 openings of their tubular extensions and are, preferably, arranged to register, that is, to be in line, in the one position in which the deep kerfs *m m m* are in line to receive lever *r*, see Figs. 3 and 4. A washer *l*, loosely mounted 65 on a part of screw *h* which is not threaded, has a radially extending detent *l'* adapted to enter the said internal slots *b' c' d'* and lock them, nut *j* and lock nut *j'* on the end *h'* of screw *h* retaining said washer and detent on 70 the latter.

The connection between the disks or tumblers *b c d* and their knobs or rings *g f e*, respectively, I have arranged in such a manner that the same may be changed, whenever 75 desired, from without, that is, without having to open the box or the lock, thereby changing the combination, as follows: The ends of the central tubular extensions of disks *b c d* are provided with a number of 80 radial slots as *d''*, see Fig. 5, arranged equidistant, while the knobs *g f e*, each, have a pin, as *e'*, adapted to engage with the said slots, respectively. Thus, by its pin engaging with the corresponding disk, each knob 85 may be placed in as many different positions, relative to its disk, as there are slots. In Fig. 5 ten slots are provided for on the tubular end of disk *d*, and its knob *e* will be marked correspondingly on its outer surface. If 90 then each of the three disks admits of ten different positions, the number of possible and available combinations will be $10 \times 10 \times 10 = 1000$, as is well understood. To change the combination, the lock is first unlocked 95 by setting the rings according to the selected combination, as only in that position will the internal slots *b' c' d'* be found to register, and screw *h* is then partly unscrewed until washer *l* with detent *l'* are well within the 100 said internal slots, when it will be possible to slide rings *g f e* toward the front of the lock sufficiently to disengage them from their disks and to then place their pins, as *e'*, into different slots, as *d''*, whereupon screw *h* may 105 be returned to the position as shown in Fig. 3. Washer *l* and nut *j* prevent screw *h* from being entirely withdrawn, thereby making it impossible to remove the rings without taking the whole of the lock apart. To unscrew 110

screw *h*, instead of the customary slot in the head of the screw, I bore out its center as shown and provide a hole, as *i*, and a slot on the periphery of the head, as *i'*, to engage with pins on a suitably formed key.

I do not wish to confine myself to the particular means shown and described for variably-adjustably connecting the tumblers with their marked rings, or for holding together all the parts of my lock, as the same may be varied to a considerable extent.

Having described my invention, what I claim as new and desire to secure by Letters Patent of the United States is:

- 15 1. In a permutation lock, the combination, of a plurality of tumblers each having independent operating means and slots and a movable detent adapted to engage the slots of said tumblers, whereby the relative positions of the tumblers and the means for turning the same may be variably adjusted.
- 20 2. A permutation lock, comprising, a plurality of tumblers provided with slots, rings for turning said tumblers, means for variably adjustably connecting the said tumblers and rings, a movable central member, means for limiting the motion of said central member, and a detent mounted on said central member for engaging the slots in said tumblers, whereby the combination may be changed.

3. In a permutation lock the combination of a screw carrying a detent, a plurality of rotary tumblers, provided with slots permitting the movement of said detent when 35 said slots are in alinement and operating rings for said tumblers removably secured thereto.

4. In a permutation lock the combination of a plurality of rotary tumblers, operating 40 rings therefor connected to the tumblers by means of pins and slots, and a movable detent adapted to be moved axially into slots in said tumblers, whereby the relative positions of the rings and tumblers may be 45 changed.

5. In a permutation lock the combination of a plurality of rotary tumblers each having a cylindrical extension and slots in the tumbler and in the cylindrical extension, a plurality of operating rings provided with pins adapted to engage the slots in the cylindrical extensions and a movable detent mounted upon a screw and adapted to engage the slots in the tumblers. 50

Signed at Brooklyn this 25 day of June 1907.

JOHN T. WHALEN.
